CLAIM

The ornamental design for a packaging container as shown and described.

DESCRIPTION

FIG. 1 is a side front perspective view of a first embodiment of a packaging container showing our new design;

FIG. 2 is an opposite side front perspective view thereof;

FIG. 3 is a side rear perspective view thereof;

FIG. 4 is an opposite side rear perspective view thereof;

FIG. 5 is a top view thereof;

FIG. 6 is a side front perspective view of a second embodiment of the packaging container showing our new design;

FIG. 7 is an opposite side front perspective view thereof;

FIG. 8 is a side rear perspective view thereof;

FIG. 9 is an opposite side rear perspective view thereof; and,

FIG. 10 is a top view thereof.

The broken lines immediately adjacent to the shaded areas define the bounds of the claimed design and form no part thereof. The broken lines in the drawings depict portions of the packaging container that form no part of the claimed design.

1 Claim, 10 Drawing Sheets
